GLOVE

George H. Wheaden, Johnstown, N. Y.

Application March 28, 1939, Serial No. 264,510

7 Claims. (Cl. 2—169)

While not limited thereto, my invention is particularly applicable to ladies' fine dress gloves and especially those formed of leather.

It has hitherto been proposed to provide an insert extending along the sides and around the tips of the fingers of a glove which is colored differently from the main body of the glove thereby making it possible to provide a pleasing color contrast between the insert and the main body of the glove. Hitherto, however, it has not been possible to take full advantage of such color contrast for the reason that it has not been possible to provide a similar color contrast in the thumb as it has been impossible to provide similar inserts in the thumb and at the same time maintain the fit of the glove.

In accordance with my invention, inserts are provided at opposite sides of the thumb which may be colored differently from the main body of the glove thereby creating a color contrast in the thumb which may correspond to the color contrast provided in the fingers and at the same time a thumb having a perfect fit is provided. Furthermore, uniformity of appearance throughout the fingers and thumb of a glove is made possible.

Other novel features of my invention will appear in the specification and will be more particularly pointed out in the claims.

My invention will best be understood by reference to the accompanying drawings in which I have illustrated a preferred embodiment thereof and in which

Fig. 1 is a plan view from the palm side of a long thumb glove embodying my invention;

Fig. 2 is a plan view of the blank from which the glove of Fig. 1 is formed;

Fig. 3 is an end view of Fig. 1 looking towards the wrist;

Fig. 4 is a plan view of an insert which is provided along one side of the thumb of a glove embodying my invention;

Fig. 5 is a plan view of an insert on the side of the thumb opposite the insert shown in Fig. 4;

Fig. 6 is a plan view of a blank from which the back of a long thumb is cut;

Fig. 6a is a plan view of the back of a long thumb cut from the blank illustrated in Fig. 6;

Fig. 7 is a fragmentary plan view of a glove provided with a long thumb made in accordance with my invention;

Fig. 8 is a section taken along the line 8—8 of Fig. 7;

Fig. 9 is a fragmentary plan view of the back 55

of a long thumb glove taken from the opposite side from that shown in Fig. 7;

Fig. 10 is a plan view of the palm side of a short thumb glove, the view being similar to that shown in Fig. 1;

Fig. 11 is a plan view of a blank similar to that shown in Fig. 2 from which the glove shown in Fig. 10 is formed;

Fig. 12 is a plan view, similar to Fig. 4, of an 10 insert for the short thumb glove shown in Fig. 10;

Fig. 13 is a plan view of an insert similar to Fig. 5 for the opposite side of the thumb of Fig. 10;

Fig. 14 is a plan view of the back of a short 15 thumb;

Fig. 15 is a fragmentary plan view of the palm side of a short thumb glove embodying my invention;

Fig. 16 is a fragmentary plan view of the back 20 of the glove shown in Fig. 15; and

Fig. 17 is a plan view of the tip of a glove thumb illustrating a modification.

Like reference characters indicate like parts throughout the drawings.

25 Referring to the drawings and first to Figs. 1 to 9, 10 indicates generally a long thumb glove embodying my invention, the palm and back of which form the main body of the glove indicated at 11 and 12, respectively (Fig. 2). The blank

30 from which the glove shown in Fig. 1 is formed is indicated generally at 101 in Fig. 2 and is cut in the general outline indicated, in the usual and well known manner. A gouge 13 is then made

35 in the palm of the glove along the full parallel lines 14 indicated in Fig. 2 somewhat to the left of the fold line 15. The upper portion of the line 14, at the left in Fig. 2 is inclined as at 16 to the parallel portions of the lines 14 to form a slit in the palm of the glove adjacent the thumb.

40 The portion of the palm of the glove from the gouge 13 to the wrist of the glove (the bottom as viewed in Fig. 2) and of the same width as the gouge is then cut from the palm portion of the glove and discarded.

45 The gouge 13 which is integral with the palm portion of the glove is then bent upwardly as viewed in Fig. 7 and forms the palm portion of the thumb of the glove.

The back or upper portion of the long thumb 50 17, as viewed in Fig. 1, is offset from the lower portion and is cut from a blank 171 indicated in Fig. 6. The upper part of the thumb is to be measured and cut at an angle, preferably approximately 25°, to the ball of the thumb and is then pulled down to a thumb pattern in which the

ball of the thumb is also at an angle of approximately 25° to the rest of the thumb as indicated in Fig. 6a, and is then punched out on a block with a die of the same size.

The insert 18 for the inner side of the thumb is cut to the form shown in Fig. 4 and comprises a longitudinally extending portion 181 and a laterally extended quirk-shaped member 19, the straight portion being sewed at one edge to an edge of the palm portion 13 of the thumb, and to the free edge of the palm 11, the opposite edge of the insert being sewed to the back portion 17 of the thumb. The quirk-shaped member 19 is received in the slit 16, the side edges of which are then spread to the position indicated in Fig. 7 and provides fullness for a proper fit for this portion of the thumb. The longitudinally extending portion 181 is preferably tapered slightly from about the region of the quirk-shaped member 19 to the end of said straight portion.

A second insert 20 of the form shown in Fig. 5 and formed with a laterally extending portion 21, preferably angular in form is provided, one end being inserted between the palm portion 13 of the thumb and the back portion 17 on the opposite side thereof from the insert 18 while the opposite end of the insert is sewed at its edges to the free edge of the back of the glove and an edge of the back 17 of the thumb, respectively. The angular portion 21 of the insert is positioned adjacent the crotch between the thumb and the palm of the glove and provides the necessary fullness for this portion of the glove, as best shown in Fig. 9. Each of the inserts 18 and 20 is tapered at one end toward the tip of the thumb to a form similar to a regular fourchette between the fingers and is of a length to extend to the wrist. The upper portion of each of said inserts serves as a fourchette.

In Figs. 10 to 16 I have illustrated my invention embodied in a short thumb glove in which parts similar to those in Figs. 1 to 9 are marked with the same reference characters with the letter *a* appended. In the form here illustrated, the gouge 13a is substantially the same as shown in Fig. 2 but merely forms an opening in the palm of the glove. When the gouge is bent up it forms the palm of the thumb as it did in the case of the long thumb and leaves an opening in the material for the thumb. The back portion 17a of the thumb is then cut from a corresponding shaped blank which is generally similar to the blank shown in Fig. 6, but shorter, and with the ball portion at an angle, preferably approximately 25°, to the top portion in the same manner as described in connection with the back of the long thumb illustrated in Fig. 6. The upper portion of the thumb is thus offset from the lower portion thereof as is the case in the long thumb shown in Figs. 1 to 9. Inserts 18a and 20a are also cut for the sides of the thumb. The insert 18a is provided with a laterally extending quirk-shaped member 19a and the insert 20a is provided with a laterally extending angular extension 21a all of which are similar to the inserts shown in Figs. 4 and 5 with the exception that the inserts of 18a and 20a are tapered more sharply than in the case of the inserts for the long thumb, and that the lower portions of the inserts extend downwardly to the base of the ball of the thumb. The provision of the thumb inserts of the form shown and described avoids puckering and insufficient fullness which would otherwise be present.

In Fig. 17 I have shown a modification of my

invention in which the two inserts 18 and 20 (or 18a and 20a, as the case may be) extend around the tip of the thumb but the pieces are preferably separate and overlapped and sewn together as at 22.

I have thus provided a thumb having four portions, namely, the palm and back portions of the thumb and inserts along the sides, all of differing shapes and interfitted about the thumb of the hand in such a way as to form a good fit.

15 By forming the back and palm of the body of the glove of one color and the fourchettes between the fingers and the inserts at the sides of the thumb of a different color, the glove presents an attractive appearance and when formed in accordance with my invention provides a good fit around the thumb as well as around the fingers.

20 While I have described my invention in its preferred embodiment, it is to be understood that the words which I have used are words of description and not of limitation. Hence, changes within the purview of the appended claims may be made without departing from the true scope 25 and spirit of my invention in its broader aspects.

What I claim is:

1. In a glove, a thumb comprising a palm portion and a back portion, the back of said thumb comprising an upper portion and a lower portion, the palm of said glove adjacent said thumb being provided with a slit, a first insert disposed between said palm portion and said back portion of said glove and provided with a laterally extending quirk-shaped member attached at its edges to the edges of said material defining said slit, and a second insert disposed between said palm portion and said back portion of said glove on the opposite side thereof from said first insert, and provided with a laterally extending projection located adjacent the crotch formed between the palm of said thumb and the palm of the glove, said upper portion being offset from said lower portion.

2. In a glove, a thumb comprising a palm portion integral the palm of said glove and a back portion, the palm of said glove adjacent the thumb being provided with a slit, a first insert disposed between the palm portion and the back portion of said thumb and provided with a laterally extending quirk-shaped member sewed at its edges to the edges of the material defining said slit, and a second insert disposed between the palm portion and the back portion of said thumb on the opposite side thereof from said first insert and provided at the portion adjacent to the crotch formed between said thumb and the main body of the glove with a laterally extending projection, each of said inserts being of a length to extend to the wrist of the glove.

3. In a glove, a palm portion and a back portion, a thumb comprising a palm portion and a back portion, the palm portion of said glove being provided with a slit located adjacent the base of the thumb, a first insert serving as a fourchette for the upper portion of the thumb and disposed between the palm portion and the back portion of said thumb, said insert being provided with a laterally extending quirk-shaped member seamed at its edges to the edges of the material defining said slit, a second insert disposed between the palm portion and the back portion of said thumb on the opposite side thereof from said first insert, said inserts serving as fourchettes for the upper portion of the thumb, the upper portion of the back of said thumb extending

ing to the end of said thumb and being offset from the lower portion.

4. In a glove, a palm portion and a back portion, a thumb comprising a palm portion and a back portion, the palm portion of said glove being provided adjacent the base of the thumb with a slit, a first insert disposed between the palm portion and the back portion of said thumb, the upper end of said insert extending to the tip of said thumb and the lower portion thereof being provided with a laterally extending quirk-shaped member seamed at its edges to the edges of the material defining said slit, a second insert disposed between the palm portion and the back portion of said thumb on the opposite side thereof from said first insert and provided with a laterally extending projection located adjacent to the crotch of said thumb, both of said inserts serving as fourchettes for the upper portion of the thumb, the lower portion of the back of said thumb extending to the wrist, the upper portion of the back of said thumb being offset from the lower portion thereof.

5. In a glove comprising a palm portion and a back portion, a thumb comprising a palm portion and a back portion, the palm portion of said glove adjacent said thumb being provided with a slit, a first insert the upper portion of which is disposed between the palm portion and the back portion of said thumb and serves as a fourchette for the upper portion of the thumb and the lower portion of which is provided with a laterally extending quirk-shaped member extending into said slit and seamed to the edges of the material defining the same, and a second insert the upper portion of which is disposed between said palm portion and said back portion of said thumb on the opposite side thereof from said first insert and serving as a fourchette for the upper portion of the thumb, said second insert being provided with a laterally extending projection substantially opposite said quirk-shaped member and extending laterally to a point adjacent the crotch of said thumb.

6. In a glove comprising a palm portion and a back portion, a thumb comprising a palm portion

and a back portion, the palm portion of said glove adjacent said thumb being provided with a slit, a first insert the upper portion of which is disposed between the palm portion and the back portion of said thumb and serves as a fourchette for the upper portion of the thumb and the lower portion of which is provided with a laterally extending quirk-shaped member extending into said slit and seamed to the edges of the material defining the same, and a second insert the upper portion of which is disposed between said palm portion and said back portion of said thumb on the opposite side thereof from said first insert and serving as a fourchette for the upper portion of the thumb, said second insert being provided with a laterally extending projection substantially opposite said quirk-shaped member and extending laterally to a point adjacent the crotch of said thumb, the lower ends of said inserts extending downwardly to points adjacent the base of the ball of the thumb.

7. In a glove comprising a palm portion and a back portion, a thumb comprising a palm portion and a back portion, the palm portion of said glove adjacent said thumb being provided with a slit, a first insert the upper portion of which is disposed between the palm portion and the back portion of said thumb and serves as a fourchette for the upper portion of the thumb and the lower portion of which is provided with a laterally extending quirk-shaped member extending into said slit and seamed to the edges of the material defining the same, and a second insert the upper portion of which is disposed between said palm portion and said back portion of said thumb on the opposite side thereof from said first insert and serving as a fourchette for the upper portion of the thumb, said second insert being provided with a laterally extending projection substantially opposite said quirk-shaped member and extending laterally to a point adjacent the crotch of said thumb, the lower ends of said inserts being of sufficient length to extend to the wrist of said glove.

GEORGE H. WHEADON.
